UNITED STATES PATENT OFFICE.

TARGE G. MANDT, OF STOUGHTON, WISCONSIN.

RUNNER FOR BOB-SLEDS.

SPECIFICATION forming part of Letters Patent No. 402,954, dated May 7, 1889.

Application filed January 19, 1889. Serial No. 296,890. (No model.)

To all whom it may concern:

Be it known that I, TARGE G. MANDT, a citizen of the United States, and a resident of Stoughton, in the county of Dane and State 5 of Wisconsin, have invented certain new and useful Improvements in Runners for Bob-Sleds; and I do hereby declare that the following is a full, clear, and exact description of the invention, which will enable others 10 skilled in the art to which it appertains to make and use the same, reference being had to the accompanying drawings, which form a part of this specification.

This invention relates to runners for bob-sleds.

The object is to produce a runner for bob-sleds provided with means for holding the rave and cross-beam in place thereon; furthermore, to produce a runner which shall be 20 simple of construction, efficient and durable in use, and comparatively inexpensive of production.

With these objects in view the invention consists in the combination, with the knee of 25 the runner of a bob-sled, of standards secured thereto extending above the cross-beam and to which the rave is secured, whereby the cross-beam will be free from the rave, and thus allow the runner of the sleigh to oscillate; furthermore, in the combination, with the runner provided with standards extending above 30 the bearing of the cross-beam to which the rave is attached, so as to allow the beam to be free from the rave in order to allow the runner to oscillate, of a flange formed in the end 35 of the runner and forming a bearing to which the end of the rave is secured, whereby the runner will be additionally strengthened; and, finally, in the various novel details of construction, as will be hereinafter fully described 40 in the specification, illustrated in the drawings, and pointed out in the claims.

In the accompanying drawings, forming 45 part of this specification, and in which like letters of reference indicate corresponding parts, I have illustrated one form of device embodying the essential features of my invention, although the same may be carried into effect in other ways without in the least 50 departing from the same.

In the drawings, Figure 1 is a perspective

view of the runner, showing the rave secured to the brackets on the knee and the cross-beam in place. Fig. 2 is a perspective view of the runner with the rave and cross-beam removed. Fig. 3 is a top plan view of the runner, and Fig. 4 is a detail view of the cross-beam.

Referring to the drawings, A designates the runner; B, the knee, which may be either secured to or made integral with the runner; C, the rave, resting upon standards D, formed on the top of the knee; and E, the cross-beam upon which the sleigh-body is secured.

In carrying this invention into effect the 65 runner A, knee B, and standards D may be made of one piece—that is, of cast metal; but, if desired, as before stated, they may be secured upon the runner in any suitable manner. Upon each side of the knee are formed 70 the standards D, upon which the rave is secured. These standards are provided on each side with ears d, formed with a recess, d', through which extend bolts d'' for holding the rave in place thereon. The end of the runner is provided on one or both sides with a flange, a, provided with openings a', through which bolts extend to hold the rave securely in place.

As shown in the drawings, only one flange 80 is used, and the outer side of the end of the runner is formed into an ear, a'', provided with a recess, a'', through which extends a bolt, a'', which passes up through the end of the rave, thereby additionally securing it. The space 85 between the two standards D forms a recess, in which fits the beam E, and the brace b, which forms the top of the knee proper, is provided with a semicircular ridge, b', forming a bearing on which the end of the beam E rests, 90 and by reason of its shape allows the said beam to oscillate, so as to present a smooth-riding runner, and one which will adapt itself to any inequality or roughness in the road. Directly below the semicircular ridge is 95 formed a groove, b'', designed to form a bearing for a U-shaped bolt which passes through the end of the cross-beam and fits in the said groove. As will be observed, the rave is entirely free from the cross-beam, so that it will 100 be allowed to oscillate without coming in contact with the said rave.

I am aware that the idea of having a rave upon a sleigh is not new; but the idea of providing the knee with standards to which to secure the rave, so as to keep it out of contact 5 with the cross-beam, and the idea of securing the beam movably below the rave are new.

It will thus be seen that by constructing a sleigh-runner with standards on the knee, so as to admit of the rave being rigidly secured 10 above the cross-beam and to the end of the runner, and by reason of the movable cross-beam an easy-riding bob-sleigh will be produced.

Having thus fully described my invention, what I claim as new, and desire to secure by 15 Letters Patent, is—

1. A runner for sleds having a knee formed integral therewith, provided with a curved bearing for the cross-beam, and standards rising from said knee provided with support-

ing-ears for the rave, substantially as de- 20 scribed.

2. A runner for sleds having a knee provided with a curved bearing for the cross-beam, and supporting-ears for the rave, the knee, and end of the runner, substantially as described. 25

3. The combination, with the knee having the curved projection or ridge, of the cross-beam having a depression in which said projection or ridge fits, substantially as and for the purpose described. 30

In testimony that I claim the foregoing as my own I have hereunto affixed my signature in presence of two witnesses.

TARGE G. MANDT.
